UNITED STATES PATENT OFFICE.

ROBERT L. COONEY, OF ATLANTA, GEORGIA.

STATIONARY FIRE-EXTINGUISHER SYSTEM.

1,075,091.

Specification of Letters Patent.

Patented Oct. 7, 1913.

Application filed November 22, 1909. Serial No. 530,467.

To all whom it may concern:

Be it known that I, ROBERT L. COONEY, a citizen of the United States, residing at Atlanta, in the county of Fulton and State of Georgia, have invented new and useful Improvements in Stationary Fire-Extinguisher Systems, of which the following is a specification.

This invention relates to new and useful improvements in stationary fire extinguisher systems and its primary object is to provide a system in which the power or influence developed by the activity of a pneumatic medium at ordinary temperature is utilized as a motive force to directly effect the operative movement of a mechanical controlling element of "primary" fire extinguisher agent supply means, the word "primary" in this connection being used with reference to an initial or sole supply of fire extinguisher agent, as distinguished from any secondary or subsequent supply that might be provided for.

A further object of the invention is to provide a system having as an additional novel characteristic the normal maintenance of two bodies of elastic fluid at equal or balanced degrees of pressure in such a relation that when one body, the "dominant" body, is subject to reduction or retraction consequent to the opening of a sprinkler head, distributing valve or equivalent device, the other body, the "servient" body (which is normally held in restraint by the "dominant" body) becomes active (*i. e.*, expands) as a consequence of the reduction or retraction of the "dominant" body to cause, by expansion or projection, the operation of a fire extinguisher agent supply means.

A further object of the invention is to provide a system in which the chemical mixing operation may be produced by the operative movement of a pressure operated plunger.

In the drawings: Figure 1 is a sectional view of a system in accordance with the present invention. Fig. 2 is a similar view in which alternative details of construction are embodied. Fig. 3 is a similar view in which other alternative structural details are embodied.

In the following description, similar characters of reference designate corresponding parts throughout the several views.

Referring more particularly to Fig. 1, the numerals 1 and 2 designate two tanks, in which the controlling elastic fluids are confined, the tank 1, containing the "dominant" body, and the tank 2, containing the "servient" body. The piping of the system is designated by the numeral 3, a single pipe, hereinafter termed the "distributing" pipe being shown. The pipe 3 and its various branches (not shown) lead to the different rooms of the building to be protected and are equipped with the usual sprinkler heads, distributing valves, or equivalent devices. To illustrate this arrangement, a sprinkler head as 2^a, is shown as fitted to the pipe 3. The latter communicates directly with the tank 1 and has an extension, as 4, which projects to near the bottom of the tank and through which the fire extinguisher agent flows, in its egress from the tank. Any means, or arrangement of means, for putting elastic fluid under pressure in the tanks and in the distributing pipe may be employed. A carboy, as 5, is shown as an example of such a means. This carboy is charged with compressed air, or a gas fatal to combustion, and may be conveniently connected to the distributing pipe 3 by a connection 6. This arrangement admits of interposing in the connection 6, certain adjunctive devices tending to promote the efficiency of the system, *e. g.* a pressure reducer, as 7, which maintains the pressure at some determined absolute degree, a pressure indicator, as 8, and a safety valve, as 9, for relieving excess pressure due to overgeneration in the case of a chemical mixing system. In the embodiments shown, the fire extinguisher agent supply means is of the chemical mixing type, and the tank 1 contains the chemical mixing means. Because of this characteristic of containing the fire extinguisher agent supply means, the tank 1 is arbitrarily termed the "primary" tank, the word "primary" in this connection being used to signify a tank in which the operation of the means for supplying the fire extinguisher

agent takes place. The tank 2 is essentially an elastic fluid container and for this reason is arbitrarily termed the "secondary" tank, the word "secondary" in this connection being used to signify a tank which, without regard to any other characteristics that it may have in a particular embodiment, is essentially an elastic fluid container.

In the example shown in Fig. 2, the tanks 1 and 2 are partially filled with liquid, the liquid in the tank 1 being an alkaline solution. Above the liquid in each tank is the space in which the compressed air or gas is confined. The extension 4 has near its upper end an opening 4^a which normally communicates with the air or gas space in the tank 1 but which is closed during the period of generation. The communication of the opening 4^a with the said air or gas space and the subsequent closing of this opening may be effected in various ways and by various means. In the apparatus of Fig. 1, these results are effected by the use of a flexible hose section, as 10, having an end joined to the extension 4 and alining with the opening 4^a, this hose section being supported in a manner to be explained. The tanks 1 and 2 are connected, at their upper ends by a pipe, as 11, which communicates with the pressure space in each tank, and at their lower ends by a pipe, as 12, which communicates with the liquid space in each tank. A check valve, as 13, having a "pin hole" opening 14, is interposed in the pipe 11, the valve 13 opening toward the tank 2, and a check valve, as 15, is interposed in the pipe 12, the valve 15 opening toward the tank 1. The "primary" tank contains an acid bottle, as 16, to the lower end of which a float, as 17, is attached. The bottle 16 stands normally in an upright position, the float 17 seating conformably on a saddle block 18 in close proximity to the end of the pipe 12 which projects some distance into the tank. The upper end of the bottle 16 is closed by a loose fitting weighted stopper, as 19, having an eye, as 20, through which the end portion of the hose section 10 projects. The bottle thus constitutes a support for the hose section, to normally hold the same in a position above the body of liquid in the tank. The pressure charge from the carboy 5 or equivalent source enters the distributing pipe and the tanks 1 and 2, flowing into the tank 1 through the hose section 10 and flowing into the tank 2 through the pipe 11.

In operation, the opening of a sprinkler head or equivalent device allows the pressure in the distributing pipe and therewith the pressure in the tank 1 to fall, suddenly and materially. At this time, the restraining "dominant" pressure having been reduced, the "servient" pressure in the tank 2 expands, violently forcing the liquid con-

tents of the tank 2 through the pipe 12. The sweep of the stream issuing from the pipe 12 unseats the bottle 16 and the latter automatically inverts, on account of the float at the bottom thereof and the weight of the acid above the float. During the inversion of the bottle 16, the weighted stopper 19 drops from the mouth thereof and at the same time pulls the hose section 10 to the bottom of the tank. The acid then runs out of the bottle and mixes with the solution in the tank to set up the generation of a gas fatal to combustion, in the well known manner.

From the foregoing description of the operation, it will be apparent that the specific apparatus disclosed herein by way of example, is not only pressure controlled but is also pressure operated, the controlling, *i. e.* the "dominant" pressure, normally holding in restraint the operating, *i. e.* the "servient" pressure. It will also be apparent that the opposed pressures are always balanced, irrespective of their absolute degree and consequently a premature operation of the system is an impossibility. The importance of keeping the pressures at an equal degree will be appreciated when it is considered that in the "dry-pipe" pressure controlled systems, it is not possible to absolutely prevent some leakage of the elastic fluid. In the present arrangement this leakage is without effect, in so far as it might otherwise tend to produce an unbalancing of the pressures and a consequent premature operation, owing to the fact of the constant balancing of the pressures. This result of constant balancing is afforded by the normal communication of the tank 1 with the distributing pipe 10 through the opening 4^a and by the normal communication of the tank 2 with the tank 1 through the "pin hole" opening 14. This "pin hole" opening, while it efficiently allows the flow of fluid from the tank 2 to the tank 1, in compensating for leakage, is too small to allow the major portion of the fluid in the tank 2 to flow into the tank 1 when the pressure in the latter is suddenly and materially reduced, and, therefore, in this event the pressure in the tank 2 expands in said tank with the result described.

In the embodiment disclosed, the operating pressure is of "positive" character. The word "positively" as used in this connection and hereinafter, does not have the meaning which it usually has in the mechanical sciences but is intended to describe a pressure which acts by expansion or projection.

In the apparatus shown in Fig. 2, a number of modified alternative details are presented. The pipe 12 in this instance, has, within the tank 1, an upward extension, as 21, terminating at its upper end in a

horizontal extension, as 22. The acid bottle, as 16^a, is pivotally supported off and below center by a bracket, as 23, and normally rests against a cup-shaped plunger 24 which is fitted over the end of the extension 22. A ball valve, as 25, is provided for closing the opening 4^a, this valve being secured to a pivoted arm, as 26, the free end of which is normally supported by the acid bottle, resting on a projection, as 27. Instead of the check valve 13, a diaphragm, as 18^b, is employed, the same being fitted in the pipe 11 and having an aperture, as 14^b, for the same purpose as the aperture 14. In this arrangement the expansion of the pressure in the tank 2, consequent to the opening of a sprinkler head or its equivalent in the manner explained, forces a column of liquid through the pipe 12 and its extensions 21 and 22. This advancing column of liquid acts against the plunger 24, forcing the same outwardly and therewith causing the movement of the acid bottle past its center of gravity. As a consequence, the acid bottle inverts and the arm 26 drops, bringing the valve 25 to its seat against the wall of the opening 4^a and thereby closing the latter.

In the arrangement shown in Fig. 3, the depending extension 4, as shown in Figs. 1 and 2, is not employed. In lieu of this depending extension, the pipe 3 is provided with a horizontal extension, as 28, to the end of which a rigid pipe section, as 29, is pivoted. The end of the extension 28 is normally open and corresponds to the aforesaid opening 4^a. This is provided for by pivoting the section 29 to the upper side of the extension 28 and by oppositely beveling the mutually adjacent end faces of the parts 28 and 29. The free end of the section 29 rests upon the upper end of the acid bottle, which is mounted as shown in Fig. 2. When the acid bottle is inverted, the section 29 drops and thereby becomes, in effect, a continuation of the extension 28, serving with the latter to conduct the liquid from the tank 1. In this arrangement the pipe 11 which connects the upper portions of the tanks 1 and 2, instead of having a comparatively large diameter and being fitted with an apertured check valve or equivalent device, as in the examples described, is shown as a capillary tube.

Having fully described my invention, I claim:

1. A fire extinguisher system including means for maintaining two bodies of elastic fluid at normally balanced degrees of pressure, means for supplying a fire extinguishing agent, a supply system through which the agent flows, a valve operable whereby the degree of pressure of one body may be initially reduced and means whereby the other pressure by virtue of its expansive na-

ture becomes active upon the initial reduction of the first pressure to cause the operation of the fire extinguisher agent supply means.

2. A fire extinguisher system including means for separately maintaining two bodies of elastic fluid at normally balanced degrees of pressure and for maintaining a body of liquid, a piping system through which the liquid may flow, a valve operable to reduce the pressure of one of the bodies and means operable by the influence of the expansive force of the other body to develop further pressure which causes the body of liquid to flow through the piping system.

3. A chemical mixing fire extinguisher system including means for maintaining two bodies of elastic fluid, gas generating means, a supply system receiving gas from the generating means, means operable whereby the degree of pressure of one fluid body may be initially reduced, means whereby the other fluid body becomes active by virtue of its expansive nature upon the initial reduction of the pressure of the first fluid body to cause the operation of the generating means, and means for maintaining the degrees of the pressures of said fluid bodies normally equal.

4. A fire extinguisher system including means for separably maintaining two bodies of elastic fluid, a piping system having an elastic fluid under pressure therein, said system being in open communication with the space in which one of the bodies of elastic fluid is confined, a distributing valve in the piping system upon the opening of which the pressure of the fluid in the space with which the piping system communicates is initially reduced, the other body of fluid being unbalanced and becoming active upon the initial reduction of the pressure of the first body, means operable when the other body of fluid becomes active upon the initial reduction of the pressure of the first body to cause the supply of fire extinguishing agent to the piping, and means for maintaining the pressures of the bodies normally equal.

5. A fire extinguisher system including means for separably maintaining two bodies of elastic fluid, means whereby one body of fluid may flow into the space occupied by the other body when the degree of pressure of the latter is reduced, a piping system in open communication with the last named body, a distributing valve in the piping system upon the opening of which the degree of pressure of the last named body is reduced, means operable to put additional pressure in the piping system when one body of fluid flows into the space occupied by the other upon the reduction of the degree of pressure of the latter when a distributing

valve is opened, and means for maintaining the degrees of the pressures normally equal.

6. A fire extinguisher system including means for maintaining two elastic fluid bodies, a piping system in communication with the space occupied by one of the bodies, means for normally equalizing the degree of pressure of the bodies to compensate for leakage, means whereby the degree of pressure of one body may be suddenly and materially reduced, and means caused to operate by the expansive action of one body when the pressure of the other body is suddenly and materially reduced to supply additional pressure to the system.

15 7. A fire extinguisher system including means for maintaining two normally balanced elastic fluid pressures, a system of piping with which one of the pressures is in direct communication, a distributing valve in said piping system, means for supplying a fire extinguishing agent and means set in operation by the stronger pressure for causing the operation of the fire extinguishing agent supply means when the other pressure is reduced by the opening of the distributing valve.

8. In a chemical mixing fire extinguisher system, in combination, a generator structure comprising two communicating tanks, chemical mixing means in one of the tanks, the other tank serving as a container for elastic fluid under pressure, a system of piping connected to the chemical mixing tank, a distributing valve in the piping system, means for putting elastic fluid under pressure in the piping system and in the tanks, means for equalizing the pressure in the tanks and for preventing the backward flow of fluid to any material degree through the fluid inlet connection of the container tank when the fluid is exhausted from the chemical mixing tank, and means for causing the pressure of the fluid in the container tank to effect the operation of the chemical mixing means in the other tank.

45 9. In a chemical mixing fire extinguisher system, in combination, a generator structure comprising a generating tank and a fluid containing tank, a system of piping directly communicating with one of said tanks, means for putting fluid under pressure in the system and in the tanks, means whereby when the pressure is reduced in one tank it is maintained in the other tank, an acid receptacle arranged to discharge its contents into the tank with which the piping system directly communicates, and means whereby the fluid under the greater maintained pressure causes the acid discharging operation of the acid receptacle.

60 10. In a chemical mixing fire extinguisher system, in combination, a primary and a secondary tank, a piping system in direct communication with the primary tank, a

distributing valve in the piping system, means for supplying an elastic fluid under pressure to the tanks and to the system, an invertible acid receptacle which, when inverted, discharges its contents into the primary tank, means for holding the acid receptacle normally against inversion and a pipe connection between said tanks and terminating adjacent said acid receptacle, said pipe connection forming the elastic fluid of the secondary tank into a jet which causes the overturning of the acid receptacle when the pressure in the primary tank is reduced by the opening of the distributing valve.

70 11. A fire extinguisher system including means for maintaining two bodies of elastic fluid, means for equalizing at all times the pressure of the bodies, means for suddenly exhausting one of the bodies, pressure producing means, and means for causing the other body to effect the operation of the pressure producing means when the first body is suddenly exhausted.

75 12. A fire extinguisher system including means for maintaining two bodies of elastic fluid separated by an intervening body of liquid, means for equalizing at all times the pressure of the elastic fluid bodies, means for suddenly exhausting one of the elastic fluid bodies, a chemical container which discharges its contents into the body of liquid, and means for causing the other body of elastic fluid to effect the discharging operation of the chemical container when the first named body of elastic fluid is suddenly exhausted.

80 13. A fire extinguisher system including means for maintaining two bodies of elastic fluid separated and at equal degrees of pressure, means for equalizing at all times the pressure of the bodies, means for suddenly exhausting one of the bodies, fire extinguisher agent supply means, and means for causing the other body to effect the operation of the supply means when the first body is suddenly exhausted.

85 14. A dry pipe fire extinguisher system, including a distributing pipe, a solution tank to which said pipe is connected, a chemical container mounted in equilibrium in said tank, the system having a source of pressure external to the chemical container, and means to cause a positive fluid impulse from said external source of pressure to directly effect the inversion of the chemical container and the discharge of its contents into said tank, said impulse being initiated by a pressure disturbance in a pneumatic medium in the distributing pipe.

90 15. A dry pipe fire extinguisher system, including a distributing pipe, a solution tank to which said pipe is connected, a chemical container mounted in equilibrium in said tank, the system having a source of pressure external to the chemical container, and

means to cause a positive fluid impulse from
said external source of pressure to directly
effect the discharging operation of the chem-
ical container, said impulse being initiated
5 by a pressure disturbance in a pneumatic
medium in the distributing pipe.

In testimony whereof I have hereunto set

my hand in presence of two subscribing wit-
nesses.

ROBERT L. COONEY.
